Egisto Pancotti, Crestwood, N. Y., assignor to Excelsior Accordions Inc., New York, N. Y.

Application December 9, 1948, Serial No. 150,045

Term of patent 3½ years

(Cl. D56—1)

To all whom it may concern:

Be it known that I, Egisto Pancotti, a citizen of the United States of America, residing at Crestwood, county of Westchester, and State of New York, have invented a new, original, and ornamental Design for an Accordion or Similar Article, of which the following is a specification, reference being had to the accompanying drawing, forming a part thereof.

Fig. 1 is a perspective view of an accordion showing my new design;

Fig. 2 is a side view thereof; and

Fig. 3 is a top plan view thereof.

The characteristic features of my design reside in the portions shown in full lines in the drawing.

I claim:

The ornamental design for an accordion or similar article, as shown and described.

EGISTO PANCOTTI.
